UNITED STATES PATENT OFFICE

ITALO FANTINO, OF NEW YORK, N. Y.

SHOE STRETCHER

Application filed February 2, 1929. Serial No. 337,095.

This invention relates to methods and means for stretching leather or other stretchable material, and more especially to a device to relieve the pressure of the shoe on bunions, 5 corns, sores, or other foot ailments.

An object of the invention is to provide a convenient and easily portable means for stretching the leather in a portion of a shoe to relieve the pressure of the shoe on the part 10 of the foot immediately beneath it.

Another object is to provide such a device adapted to stretch a longitudinal portion of either the right or left shoe while permitting easy access to the operating portion of the 15 device from the upper opening of the shoe.

A further object is to provide the device with replaceable means adapted to affect either the elongated area covering a bunion or a substantially circular area covering a 20 corn.

Finally, an object is to provide such a method and means which is simple in operation, has a minimum number of parts, can be manufactured economically from suitable 25 castings, and is yet attractive and salable in appearance.

All these and other objects as suggested below are attained by the methods and means now to be described, and illustrated in the accompanying drawing, in which—

Figure 1 is a perspective view, partly in phantom, of one preferred embodiment of the device in operative position in a shoe to show its method of use.

Fig. 2 is a side elevational view, partly in section, of the completely assembled stretcher.

Fig. 3 is a detailed fragmentary view of the looped end portion of the stretcher, showing how it can be reversed in its socket to extend 40 in an opposite longitudinal direction when used on an opposite shoe.

Fig. 4 is a detail of the knob-like end portion of the device adapted for use with a bunion or other horizontally positioned foot ailment and showing the method of altering its position to conform to the altered position of its complementary loop-like portion as disclosed in Fig. 3.

Fig. 5 is a circular loop-like end portion 45 adapted to be substituted for the oblong loop-

like end portion shown in Fig. 1 when the device is to be used to relieve pressure on a corn for instance, which is usually nearly circular in outline.

And Fig. 6 is a replaceable knob-like portion, for use with Fig. 5, adapted to replace the oblong shaped knob-like portion illustrated in the previous views.

Like numerals refer to like parts throughout the several views.

The method usually employed in shoe stores and elsewhere for relieving or stretching a shoe to relieve the pressure on a corn or bunion or other localized area is by means of a device which stretches a considerable portion 65 of the surrounding area of the shoe as well. Applicant has devised a simple means for quickly and easily stretching only the exact area needed to relieve the pressure at that point. The method and means used is shown 70 clearly in Fig. 1, where the device is in position on a right shoe 10 for relieving the pressure on a bunion.

The device consists essentially of a metallic (or like) arm 11 pivoted at 12 to the right-angle projecting end 13 of a companion arm 14 which may also be made of metal, wood, or other suitable material.

The outer end of arm 11, Fig. 2 is recessed to receive a loop-shaped end portion 15 in 80 either of two positions turned 180 degrees from each other. Member 15 is replaceably secured to arm 11 by means of stud bolt 16 extending through both members and a pin 17 extending across the recess of member 11 and 85 engaging an open slot in the end of member 15.

In the embodiment shown in Fig. 2 the arm 11 instead of terminating in a closed recess is arch-shaped in cross section to accomplish the 90 same purpose while yet simplifying manufacture.

Detachably secured to the outer end of member 14 is an oblong shaped knob-like member 18 pivotally held to the flattened end 95 of member 14 by means of bolt 19 with its nut 20.

Knob 18 has a washer 21 with an upwardly projecting lip 22 integrally secured to its flat surface as shown; and there is a recessed arc- 100

like portion in the outer flattened end of member 14 as shown in Fig. 4, against the ends of which lip 22 is adapted to engage to limit the movement of member 18 to two extreme positions, as shown by solid and dotted lines in Fig. 4, to accord with similar positions of the companion loop member 15 when in either of its two reversed positions, as in Fig. 3. Nut 20 is screwed down tight enough to permit member 18 to assume either position desired by being pivoted around bolt 19, and held in the desired position by friction.

Pivots secured to member 14 at 24, Fig. 2, at approximately one-third the length of member 14 from its pivoted end, is a threaded locking member 24 equipped with a wing nut 25 adapted by being screwed down to bring the outer loop end of member 15 around the outer knob-like end 18 of member 14.

23 Threaded member 24 is loosely pivoted at 23 and extends through an over-sized hole in member 11 to prevent binding at any angular position between the two arm members 11 and 14.

26 The construction previously described is for use primarily in relieving pressure on bunions. To adapt the device for use with corns, it is but necessary to substitute the knob-like circular member 25, Fig. 6, for the 28 oblong shaped member 18, and to just fit around knob 25, for the oblong-shaped loop member 15, by the removal and replacement of bolt 16. Likewise, any desired combination of shapes or companion parts may be substituted to adapt the device to all needs.

In the operating of the device it is but necessary to unscrew wing nut 25 sufficiently to completely separate knob 18 from loop 15 and then introduce the device into the shoe in the manner shown in Fig. 1 with member 15 preferably on the outside of the shoe over the portion desired to be stretched. Wing nut 25 is then screwed down, bringing knob 18 within loop 15, with the leather or other material 40 of the shoe in between, there being only sufficient distance between the outer surface of the knob and the loop to accommodate it. Continued turning of the wing nut 25 will then stretch the leather into the convex shape 45 of knob 18 and so relieve the pressure of the shoe at this point. The device is similarly used with any other knob and loop, shaped as suggested for instance in Figs. 5 and 6. By reversing the position of member 15 in arm 11 and pivoting knob 18 to conform thereto, the device is adapted for use in the same position on the other side of the same shoe or the same side of the opposite shoe. It will be apparent that many allied uses and different 55 combinations of the same use of this device can be obtained for different portions of the shoe requiring stretching.

It is to be understood that the present disclosure is for the purpose of illustration only, 65 and that the invention is not limited thereto.

To those skilled in the art, many modifications of the invention will be readily apparent, and it will also be obvious to such skilled persons that parts of the device and method may be used without other parts thereof, 70 many such combinations readily suggesting themselves. Therefore, it should be, and is to be distinctly understood that for a definition of the limitations of the invention, reference must be had to the appended claims. 75

Having now described the invention what is claimed as new and for which Letters Patent of the United States is desired, is:

1. A device for stretching shoes including an oval-shaped loop member positioned diagonally on a shank and a knob-like member of like contour adapted to be moved into the loop member to stretch the material of the shoe positioned therebetween. 80

2. In a shoe stretcher an arm, a detachable member fitted to one end thereof and terminating in an angularly-disposed oblong loop, a second arm pivoted to the first arm and having its opposite end pivotally supporting a knob-like member adapted to fit 90 within the loop of its companion member when the two arms are brought together, the loop member being adapted to be reversed in position to alter its angular disposition and the knob-like member being adapted to be pivoted to either of two positions to conform thereto. 95

3. The invention as in claim 1, the diagonal positioning of the loop member on the shank being reversible to an opposite diagonal position, and the knob-like member being likewise reversible to conform thereto. 100

Signed at New York, in the county of New York, and State of New York, this 21st day of January, 1929.

ITALO FANTINO.
